UNITED STATES PATENT OFFICE.

MICHAEL TRESCHOW, OF COPENHAGEN, DENMARK.

BOILER FOR HEATING SYSTEMS OR SIMILAR PURPOSES.

Application filed April 28, 1926, Serial No. 105,328, and in Denmark May 16, 1925.

It is well known that the amount of heat given off by the heating surface of a boiler depends to a great extent upon the rapidity of the circulation of the water surrounding the heating surface. In steam boilers, for instance, the difference between the temperature of the water in the boiler and the temperature of the combustion gases is less than in hot-water boilers, as the latter will have a much lower mean temperature of the water, but in spite of this fact the heat transmission per unit (sq. ft.) of heating surface of a hot-water boiler will, if anything, be less than the heat transmission of the corresponding steam-heating boiler. This is due to the fact that ordinarily there will always be a lively circulation of the water in a steam boiler on account of the generation of steam which takes place near the parts of the heating surface which are subjected to the most intense heat, while in the ordinary hot-water boiler,—in which no steam generation takes place—there will be practically no circulation, the velocity of the water cooled-off in the heating system being lost as the water enters the boiler, and owing to the comparatively great sectional area of same, the water passes the heating surface at a very low speed (generally on the counter-current principle). As a rule there will be no local circulation.

The fact that the water in a hot-water boiler is relatively stagnant has for such boilers not only the drawback that the heat transmission of the heating surface will be less than necessary, but it entails further the drawback that the parts of the heating surface which are especially exposed to the fire are liable to become overheated, which again may result in leakage. This is, for instance, a common occurrence in hot-water (smoke) tube-boilers, where the tube-plate facing the combustion chamber, particularly in vertical boilers where the tube-plate is arranged horizontally, very often due to overheating will become leaky at the places where the tubes are expanded into the plate, and these frequent leakages will result in a too rapid destruction of both tubes and plates, even if the tubes are re-expanded.

The use of vertical (smoke) tube-boilers has been greatly restricted by these drawbacks, although it often would prove convenient to use such boilers, as they offer advantages in economy in floor space. In horizontal tube-boilers certain devices have been

applied to set up a rapid circulation of the water near the exposed tube-plate of the boiler. Such well-known devices, however, can not be applied to vertical tube-boilers. 60

The drawing shows an example of how the invention may be applied to a hot-water boiler of the above mentioned kind and provided with a fuel magazine.

Fig. 1 shows a vertical section of the 65 boiler according to the invention, and

Fig. 2 a section following the line A—B in Fig. 1.

As an example the boiler is shown having a fire space with sloping grates for the 70 combustion of bituminous fuel, but a horizontal grate may also be used.

By a partition *b* with double partition-walls the fire box *a* is divided into two portions, the fire box proper with the combustion chamber *c*, and the smoke box *d*. As will be seen from Fig. 2 the partition *b* is closed at both ends, forming a flat tube the lower end of which, in the present design, is shown entering the lower part of the 80 boiler, i. e., in the water space between the bottom plate of the fire box *a* and the bottom plate *e* of the boiler proper, and the upper end of which is entering the upper part of the boiler right above the lower tube-plate *f*. The partition *b* may be arranged 85 either vertically or inclined. Through the smoke tubes *g* the gases pass from the combustion chamber *c* to a header *h*, down through the boiler tubes *i*, to the smoke box *d* and hence to the chimney.

The water in the partition *b*, above the upper entrance of which a guide plate *k*, Fig. 1, may be provided, will become intensively heated, exposed as it is to the heat 95 from two sides, from the combustion chamber *c* and the smoke box *d*, thereby causing a large volume of water, eventually intermixed with steam bubbles to flow from the bottom of the boiler upwards through the 100 partition *b* to the space above the fire box, where it is distributed across the tube-plate, thus preventing overheating of the same. The downward circulation of the boiler-water will mainly take place at the back 105 front of the boiler, between the back plate of the latter and the back plate of the fire box (smoke box), as indicated by the arrow *x* in Fig. 1.

The cooled-off return water from the heating system may, for instance, enter the boiler 110 in the rear end, and the water heated in the

boiler should preferably leave the boiler from the upper plate, through one or more flow pipes 1.

Having thus described my invention, what 5 I claim is:-

1. Vertical boiler for heating systems having upright smoke tubes as heating surface and the fire box divided into a combustion chamber and a smoke box by means of a partition consisting of two spaced walls, said partition forming a direct communication between the upper and lower parts of the boiler.

2. Boiler for heating systems having ver-

tical smoke tubes as heating surface and a 15 partition consisting of two spaced walls between the combustion chamber and smoke box of the boiler, said partition forming a communication between the upper and lower parts of the boiler, a guide plate provided 20 above the entrance of the partition into the upper part of the boiler, said plate being positioned to distribute the water rising in the partition across the most intensively heated portion of the tube plate. 25

In testimony whereof I have signed my name to this specification.

MICHAEL TRESCHOW.
